US00D613294S

(12) **United States Design Patent**
Lee et al.

(10) **Patent No.:** US D613,294 S
(45) **Date of Patent:** ** Apr. 6, 2010

(54) **HOUSING FOR A MOBILE COMPUTING DEVICE**

(75) Inventors: **Stephen Lee**, San Francisco, CA (US);
Lawrence Lam, San Jose, CA (US);
Troy Hulik, Saratoga, CA (US)

DESCRIPTION

FIG. 1 is a front isometric view of a housing for a mobile computing device;

FIG. 2 is a front view of the housing of FIG. 1;

FIG. 3 is a bottom side view of the housing of FIG. 1;

FIG. 4 is a top side view of the housing of FIG. 1;

FIG. 5 is a first side view of the housing of FIG. 1; and,

FIG. 6 is a second side view of the housing of FIG. 1.

The broken line showing of portions of a mobile computing device forms no part of the claimed design.

1 Claim, 3 Drawing Sheets
